(57) **CLAIM**

The ornamental design for an ergonomic optical disk unwrapping device, as shown and described.

DESCRIPTION

FIG. 1 is a right front elevational perspective view of the optical disk unwrapper of the present invention.

FIG. 2 is a left rear elevational perspective view of the optical disk unwrapper of the present invention.

FIG. 3 is a left side view of the invention.

FIG. 4 is a right side view of the invention.

FIG. 5 is a bottom view of the invention; and,

FIG. 6 is a top view of the invention.
